Charles H. Straffin

UNITED STATES PATENT OFFICE.

CHARL S H. STRAFFIN, OF BOSTON, ASSIGNOR TO HIMSELF AND JAMES H. PARKER, OF NATICK, MASSACHUSETTS.

IMPROVEMENT IN BRACKET-SHEAVES.

Specification forming part of Letters Patent No. 125,419, dated April 9, 1872.

To all whom it may concern:

I, CHARLES H. STRAFFIN, of Boston, in the county of Suffolk and State of Massachusetts, have invented a certain new and useful Bracket-Sheave, of which the following is a specification:

The Nature of the Invention.

The nature of my invention consists in combining, with an open sheave-block, a plate at right angles to the plane of the pulley, said plate being provided with screw or nail-holes by means of which the sheave may be fastened to the post or support; the whole being an article of manufacture.

Description of the Accompanying Drawing.

Figure 1 is a perspective view of my invention. Fig. 2 is a vertical section of the same.

General Description.

Let A represent the pulley held by the open

block B, the block B being open at D so that the line may be easily put in position. E is a plate cast at right angles to the block B, and is provided with screw or nail-holes H H H, by which the sheave is to be made fast to the support.

I am aware that open sheaves have been made before; and I therefore confine myself to the cast metallic bracket-sheave as an article of manufacture.

I claim as my invention—

The cast metallic sheave as an article of manufacture, consisting of the parts A B E, substantially as described, and for the purpose set forth.

CHARLES H. STRAFFIN.
